UNITED STATES PATENT OFFICE.

EDGAR L. DAVIS, OF CARROLLTON, ILLINOIS.

AUTOMATIC VALVE.

SPECIFICATION forming part of Letters Patent No. 770,845, dated September 27, 1904.

Application filed February 19, 1904. Serial No. 194,440. (No model.)

To all whom it may concern:

Be it known that I, EDGAR L. DAVIS, residing at Carrollton, in the county of Greene and State of Illinois, have invented a new and useful Improvement in Automatic Valves, of which the following is a description, reference being had to the accompanying drawings, which are a part of this specification.

My invention has relation to improvements in valves of a class wherein the valve is operated upon automatically by means of a float resting on the water, which rises and falls as the water in the vessel rises and falls.

The object of my invention is to provide a compact device which is self-contained and which can be applied to any tank or boiler with the minimum amount of labor and when applied all the working parts are in perfect line and will remain so regardless of the springing of the pipes which may be connected thereto and whereby the water in said tank or boiler may be automatically kept at a desired level.

With the above primary object in view the invention consists of the devices and parts or their equivalents, as hereinafter set forth.

In the accompanying drawings, Figure 1 is a vertical section of the entire device attached to a plate. Fig. 2 is an elevation of the valve, showing recess for self-adjusting ring, also of the slotted arm. Fig. 3 is a top view of self-adjusting ring. Fig. 4 is a side view of Fig. 3. Fig. 5 is a side view of lever, to which is pivoted the rod which suspends the float. Fig. 6 is an edge view of Fig. 5. Fig. 7 is a side view of the bolt by which the lever shown in Figs. 5 and 6 is pivoted. Fig. 8 is a side view of the right-angled bend in the rod which suspends the float.

Similar characters refer to similar parts through the several views.

Referring to the drawings, the letter *a* indicates the valve-chamber, provided with the slot *a'* passing through one side; *b*, the valve-seat; *c*, the valve; *c'*, the recess formed to admit the self-adjusting ring *c''*, (more clearly shown in Figs. 2, 3, and 4;) *d*, the arm, having the elongated opening *d'* passing through it; *e*, the bar extending outwardly from the valve-chamber *a*, having an eye formed in its

outer end; *f*, the bend which is attached to the valve-chamber *a* by means of its threaded end and to which the pipe *g* is attached by means of threads cut on its end.

g' is a plate through which are openings to admit the ends of valve-chamber *a* and pipe *g*.

h h' h'' h''' are set-nuts which secure the valve-chamber *a* and pipe *g* to plate *g'*; *i*, the threaded cap which covers the upper end of valve-chamber *a*; *i'*, the oil-cup; *j*, the hanger extending downward from the plate *g'*; *k*, the lever, which is loosely pivoted to the hanger *j* by means of the bolt *j'*, (see Fig. 7,) passing through said hanger *j* from the opposite side; *k'*, the bolt which passes freely through the elongated opening *d'* in arm *d*, said bolt shown more clearly in Figs. 5 and 6; *l*, the opening (see Fig. 6) through which the end of rod *n*, attached to the float *m*, passes.

In the valve-chamber *a* immediately above the valve-seat *b* are openings 1 2 3.

It will be seen by referring to the sectional view of my device in Fig. 1 that I provide for the compact self-contained device by constructing the valve-chamber *a* and valve-seat *b*, with openings 1 2 3, in one piece, the upper end of which is threaded to admit of set-nuts being turned thereon. This threaded end passes through the plate *g'*, with one set-nut, *h*, at the under side and the other set-nut, *h'*, at the upper side. The feed-pipe *g*, on which are set-nuts *h'' h'''*, also passes through plate *g'*. By tightening these set-nuts the whole construction is rigidly held to plate *g'*. The valve *c* is placed in the chamber *a*, and the arm *d*, passing through the slot *a'* in the chamber *a*, is turned firmly into said valve *c*.

From the under side of plate *g'* is the hanger *j*, extending downward, so that the center of the hole in its lower end is in line with the center of the slot *d'* in the arm *d* when the valve *c* is resting on its seat *b*. The lever *k* is then pivoted to the hanger *j* by means of the bolt *j'* (see Fig. 7) passing through it being turned firmly into lever *k*, thus leaving it free to turn thereon. The bolt *k'* (see Fig. 6) is then passed through the opening *d'* in the arm *d* and firmly turned into lever *k*. Passing through the opening *l* at the other end of lever *k* is the right-angled hook at the end 100

(see Fig. 8) of rod *n*. This rod *n* passes through guide-bar *e*. At the other end of this rod *n* is attached the float *m*.

In the foregoing description I have shown 5 the bend *f* as a separate part, being attached to chamber *a* by means of threads cut on the male end of said bend. I do not wish to be understood to bind myself to this particular form. I may preferably form the whole valve- 10 chamber *a* and bend *f* in one piece.

The operation of my invention from the foregoing description will be readily understood. As the water in the reservoir falls 15 the float *m* correspondingly falls, thus drawing down lever *k*, which in turn raises the opposite end at *k'*, which, by reason of its being pivoted to hanger *j* and also its engagement with the arm *d* by means of the bolt *k'* passing through the elongated opening *d'* of 20 the arm *d* and from the fact that said arm *d* is fixedly attached to valve *c*, said valve *c* is made to rise and leave its seat *b*, thus allowing the water to pass through said seat *b* and flow through the openings 1 2 3 into the reservoir 25 until the water in said reservoir shall rise to high-water mark, when it will raise float *m* and close the valve *c* on its seat *b*. When the device is applied to a steam-boiler, the operation is precisely the same, with the exception 30 that when the valve *c* is raised from its seat *b* steam will pass through the openings 1 2 3 and follow the bend *f* and pipe *g* to the pump, (not shown,) automatically starting said pump, which will force water into the boiler through 35 a pipe (not shown) until at high-water mark the raising of the float *m* will close valve *c* on its seat *b* and by so doing shut off the steam and stop the pump.

What I claim as my invention is—

- 40 1. In an automatic valve the combination of a plate having a hanger attached to its under side said hanger carrying a lever at the one end of which is suspended a float, openings passing through said plate to admit ends 45 of valve-chamber and pipe which are firmly held thereto by means of jam-nuts a valve-chamber having an elongated opening in one side thereof, a valve therein, said valve provided with an arm having an elongated opening in its outer end, projecting from one side thereof and passing through opening in the side of valve-chamber and adapted to engage with the free end of lever carried by the hanger attached to the under side of the plate.
- 50 2. In an automatic valve, the combination of a plate having a hanger attached to its under side, a valve-chamber having elongated slot in one side of same, openings through said valve-chamber over valve-seat, a valve 55 therein said valve provided with an arm having an elongated slot in its outer end projecting from one side thereof and passing through

opening in side of valve-chamber and adapted to engage with the free end of the lever which is pivoted to the hanger, to which (lever) at 65 its opposite end is suspended a float which rests on the water in the reservoir and when the water rises and falls the valve in the valve-chamber will rise and fall by means of its engagement with the lever to which is attached 70 the float substantially as set forth.

3. In an automatic valve the combination of a plate with hanger attached to under side, a valve-chamber, having an elongated opening in one side thereof, with valve therein, 75 said valve provided with an arm projecting from one side thereof and passing through opening in the side of valve-chamber and adapted when operated upon by the rising and falling of the water in the reservoir 80 through the means carried by the hanger attached to the under side of the plate said valve in valve-chamber will also rise and fall.

4. In an automatic valve, the combination of a plate having a hanger attached to its under side, a valve-chamber having elongated slot in one side of same, openings through said valve-chamber over valve-seat, a valve, 85 said valve provided with an arm projecting from one side thereof and passing through slot in the side of valve-chamber, a lever pivoted to the hanger attached to the under side of plate, said lever engaging at one end to the arm and adapted when the free end of said lever is operated upon by the rising and 90 falling of the float on the water in the reservoir 95 said valve will also rise and fall.

5. In an automatic valve, the combination of a plate having holes therein for valve-chamber and pipe, a hanger attached to the under side of said plate, a valve-chamber having elongated slot in one side of same, openings through said chamber just over the valve-seat, a guide-rod with an eye formed in its outer end, extending from the side of valve-chamber, a 105 valve, said valve provided with an arm having an elongated opening in its outer end projecting from one side thereof and passing through the slot in the side of valve-chamber, a lever pivoted to hanger attached to the under side of plate said lever loosely engaged at one end to arm, a float, a rod attached to said float and passing through the eye of the guide-rod projecting from side of valve-chamber and adapted so that as the float rises and 110 falls the valve in valve-chamber will rise and fall all substantially as set forth.

In testimony whereof I affix my signature in presence of two witnesses.
